UNITED STATES PATENT OFFICE.

DONALD E. WILLARD, OF DANVILLE, ILLINOIS, ASSIGNOR TO ALLITH PROUTY COMPANY, OF DANVILLE, ILLINOIS, A CORPORATION OF DELAWARE.

SPRING HINGE.

Application filed June 30, 1924. Serial No. 723,222.

My invention relates to double acting spring hinges for swinging doors and to that class of spring or floor hinges having a post or pivot with a plunger acting against a spring in combination with a pivot, the reaction of which tends to turn the door to its normal or closed position.

An object of the invention is to provide a spring hinge having a plunger of flat metal with side guides therefor.

Another object of the invention is to provide a spring hinge adapted for application to a swinging door, which hinge has means for preventing vertical and lateral displacement of the plunger in service.

Another object of the invention is to provide a spring hinge having a reciprocable plunger and guides therefor disposed between the compression spring and the pivot, which guides function to prevent lateral and vertical displacement of the plunger in service.

A still further object of the invention is to provide a spring hinge so constructed and applied as to permit the use of interchangeable side plates therefor.

Another and further object of the invention is to provide a spring hinge so constructed as to have a base plate for attachment to a floor with separate finish plates for said base plate, which finish plates may be applied to the base plate after the hinge is installed.

A still further object of the invention is to improve spring hinges for successful commercial use.

The above recited and other objects of my invention will be clearly understood from the following description and drawings, and will be particularly pointed out in the appended claims.

Fig. 1 is a side elevation of the preferred embodiment of the invention as applied to a swinging door, the latter being shown in fragmentary form.

Fig. 2 is a top view, partially in section, of the hinge of Fig. 1.

Fig. 3 is a perspective view of one of the side plates of the invention.

Fig. 4 is a fragmentary portion of a door showing in perspective the appearance of the side and end plates at the sides of the door for finishing purposes.

Fig. 5 is a perspective view of the finishing plates for the base plate.

A door 10, a fragmental portion of which is shown in the drawing, has its lower rear portion cut away on the lines 11 and 12, thus providing a recess.

The hinge of my invention includes top 60 and bottom frame members formed of strip steel, the top frame member 13 being straight and the bottom frame member 14 having its ends upturned in unequal lengths as at 15 and 16, the upturned end 15 being 65 considerably shorter than the other end 16. The end 15 is provided with a tenon which engages a properly disposed recess in the top frame member 13 (not shown) for the purpose of fastening these parts together. The 70 rear end of the top frame member 13, that is, the end shown at the left, Fig. 1, is provided with a tenon (not shown) which engages with a suitably disposed recess in the upturned end 16 of the bottom frame 75 member 14. The upturned end 16 is extended considerably above the top frame member 13 and serves as a means for fastening the hinge in position in the recess in the door. It will be observed that the front end of the 80 top frame member 13 projects beyond the upturned end 15 of the bottom frame member and is provided with an opening 17 for the reception of attaching means such as a screw 18. The upturned end 16 is provided 85 with suitably disposed openings 19 for the reception of attaching means such as screws 20.

For securing the hinge to the floor a base plate 21 is provided having a plurality of 90 openings 22 therein for screws or like fastening devices whereby the base plate may be securely fastened to the floor. At the center of the base plate 21 a pivot 23 is inserted in a suitably disposed opening which 95 pivot is non-rotatably fastened therein by a shrinking fit and with the exposed end thereof peened. Pivot 23 passes upwardly through an opening 24 in the lower frame member 14 and at 25 is reduced in diameter. 100 Mounted on the pivot 23, with the lower member resting against the shoulder formed at 25, are upper and lower plunger bearing roller frame members 26 and 27. These members 26 and 27 are shaped as shown in 105 Figs. 1 and 2 of the drawings and support near the outer ends vertically disposed studs 28 and 29 on which are disposed rollers 30 and 31. Bushings 32 are interposed between the studs 28 and 29 and the rollers 30 and 31, 110

as shown. These frame members 26 and 27 are non-rotatably mounted on the pivot. The reduced portion of the pivot 23 extends upwardly through a suitably disposed opening 5 in the upper roller frame member 13. Interposed between the upper roller frame member 26 and the frame member 13 of the hinge frame is a ball race 33 which is circular in plan and shaped to receive balls, 10 indicated by dotted lines, for bearing purposes. The central portion of the ball race is continued upwardly, forming a hollow collar 34 which serves as a bushing between the upper frame member 13 and the reduced portion 35 of the pivot. The ball race and its accompanying collar 34 are for the elimination of wear on the pivot, at this point. The ball race and its collar are so associated with the upper frame member 13 as to turn 15 with it as the same is swung about the pivot 23 in service. The studs 28 and 29 forming the axes of the rollers 30 and 31 lie in a plane which is vertical to the top and bottom frame members 13 and 14 of the end and 20 which is perpendicular to the longitudinal axis thereof.

A reciprocable plunger A is provided for longitudinal movement as the hinge is swung with the door about the pivot 23. The 25 plunger is formed preferably of flat metal and is of uniform thickness throughout. Viewed in plan as seen in Fig. 2, the plunger is made with different widths. The greatest width is at 36 where the width is slightly greater than the distance between the centers of the studs 28 and 29 of the bearing rollers 30 and 31. There is an intermediate portion 37 of less width than 36 together with an end reduced portion 38. At the 30 junction of the portions 36 and 37 shoulders 39 are formed, while the junction between the portions 37 and 38 is preferably curved. The length of the plunger when the hinge is in normal position, that is the position 35 occupied when the door is closed, is such that the one end rests against the rollers 30 and 31 and the end of the smallest portion 38 extends through opening 40 in the upturned end 15 of the lower frame member 14. This 40 end extends a sufficient distance from the upturned end 15 as to provide a suitable bearing for this end of plunger when at rest. A compression spring 41 is interposed between the upturned end 15 of the lower frame member 14 and the shoulder 39 formed on the plunger. The end of the portion 36 of the plunger A at its central part 45 is provided with a recess 42 described by an arc the radius of which is the radius of either of the rollers 30, 31.

As means for guiding the plunger A in its longitudinal movements I provide a pair of side guides 43 and 44 of flat strip metal which guides are formed with tenons at the 50 top and bottom ends to cooperate with suit-

ably disposed openings in the top and bottom frame members 13 and 14 of the hinge frame. The central portion of each of these guide members is offset forming a recess 45 which receives the side edges of the widest portion 36 of the plunger A. The vertical distance of the recess is but slightly more than the thickness of the plunger A. The side guide members 43 and 44 are so positioned that the recesses 45 engage the side edges of the portion 36 of the plunger A, and at the same time tend to restrain vertical displacement of the plunger by reason of the recesses. In this wise the plunger is guided in its longitudinal movements by the side guides 43 and 44 at the rear end and by the opening 40 in the upturned end portion 15 of the lower frame member 14 of the end frame.

The operation of the hinge is as follows: 35 The hinge is applied to a door in the recess defined by the lines 11 and 12 of Fig. 1 with the upper frame member 13 fastened to the door by means of the screw 18 and the upstanding portion 16 of the lower frame member by means of the screws 20 as shown. The base plate 21 is fastened to the floor by screws passing through the openings 22 therein. As the door is swung to either side of the pivot the rollers will be held against relative movement with respect to the pivot 23, the plunger, therefore, is reciprocated, as the rear end of the portion 36 of the plunger bears against either of the rollers 30 or 31. Such reciprocation of the plunger tends to compress the spring 41 so that when pressure on the door is released the spring will tend to expand thus moving the door automatically to closed position. Looking at the device as shown in Fig. 2, suppose the door is swung so that the hinge is moved upwardly, whereupon the plunger A would bear against the roller 30 and move therealong, depending upon the extent to which the door is opened until the door reaches fully opened position, whereupon the recess 42 in the plunger would engage the roller 30 and when the pressure on the door is released, such engagement would tend to hold the door in opened position. A slight pressure in the opposite direction would release engagement of the recess 42 with the roller and the spring 41 would thereupon tend to close the door. Movement of the door in the opposite direction would cause the plunger to bear against roller 31 in like manner.

In the past it has been customary to provide side plates for covering the hinge and the recess in the door, which plates have been made as rights and lefts, and so applied to the door and which have included protuberances to accommodate the various parts of the hinge as the door is swung. Because of different finishes of rooms, these 120

plates have been finished in different manners, necessitating the carrying in stock by jobbers and dealers of many spring hinges having various finishes of the side plates 5 and of the base plate.

My invention contemplates the use of side plates which are interchangeable as to each side of the door so that a dealer may carry in stock a supply of hinges and then 10 a supply of side plates which are applicable to the hinge so that the customer may purchase side plates having the desired finish to correspond with the finish of the rooms between which the door having this hinge 15 applied is mounted.

In Fig. 3 I have shown in perspective one of these interchangeable side plates. It is noted that the side plate comprises a body portion which is offset, having some 20 depth, which depth is sufficient to clear the top and bottom roller bearing frame members 26 and 27 at the time the plates are applied to the door. At one end of the plate there is provided a flange 46 which is perpendicular to the face 47 of the plate. At 25 the top and bottom of the flange there are provided elongated openings 48, while cut out portions 49 are formed in the margin of the flange. These opening and cut out portions 30 are for the reception of screws or similar attaching means to fasten the plates in position. The other end of the plate is provided with screw openings 50 to receive screws which are driven into the door. Two 35 such plates are required to cover the hinge of my invention.

For finishing the rear edge of the door a plate 51 is provided shaped in section to correspond to the curvature of the rear edge of 40 the door. A plurality of screw openings 52 are provided which register with the upper cut out portions 48 and the upper portion 49 of the side plates when the same are in position. An additional screw opening 45 53 is provided as a further fastening means.

In Fig. 5, I have shown two correspondingly shaped finishing plates for the base plate 21. Each of these plates is made to 50 cover one half of the base plate and each is provided with a centrally disposed cut out portion 54 for encircling the pivot 23. These plates are provided with downwardly 55 extending marginal portions 55 to overlie the marginal portions of the base plate 21. Screw openings 56 are provided and adapted to register with the opening 22 in the base plate 21. In this manner it is possible to provide separable finishing plates for the 60 base plate to correspond with the finishes of the side plates so that the dealer need not carry in stock door hinges having base plates made up of various kinds and types of finishes, such as are required in the building 65 specifications of the present time.

A floor hinge constructed in accordance with my invention I have found to be far superior to the present type on the market as to endurance, ease of operation and the elimination of trouble. Furthermore by provision of the interchangeable side plates and base plates I am enabled to supply the trade with side plates and base plates finished in various manners for application to floor hinges which are supplied to the dealers without any finish thereon whatsoever. 70

While I have described more or less precisely the details of construction of my invention, yet I do not wish to be understood as limiting myself thereto, as I contemplate 80 changes in form and the proportion of parts and substitution of equivalents as circumstances may suggest or render expedient without departing from the spirit of my invention. 85

I claim:

1. A spring hinge having a tongue formed of flat metal and with a portion of its length reduced in width, side guides for said tongue adapted to cooperate with the widest 90 portion thereof and bear against the side edges of the same, said guides extending parallel to said plunger.

2. A spring hinge having a reciprocating plunger therein formed of flat metal having 95 a portion of its length reduced in width, and three bearing members therefor, one of which is adapted to engage the reduced portion of the member and the other two adapted to engage the widest portion of said member on opposite sides thereof, said guides extending parallel to said plunger. 100

3. A spring hinge having a reciprocating plunger therein, said plunger having one end reduced in width, a guide integral with 105 the hinge frame for supporting said reduced end of the plunger, and other guide members also integral with the spring frame members disposed on opposite sides of the same adapted to engage the marginal 110 portions of a wider part of said plunger lengthwise of the guides for preventing vertical and lateral displacement of the same in operation.

4. A spring hinge including in combination, a frame, a compression spring disposed lengthwise of the frame and with one end of the spring bearing against a front end member of the frame, a pivot member near the other end of the frame, a plunger extending through the spring and the front end member of the frame with the other member thereof against the pivot member, said plunger having shoulders serving as abutments for the other end of the spring, and side guide members for said plunger formed of flat metal and attached to the top and bottom members of the frame and lengthwise thereof, said guide having offset 125 portion adapted to receive portions of the 130

plunger rearwardly of the shoulder thereof for preventing lateral and vertical displacement of the plunger in service.

5. A spring hinge including in combination, a frame member, a spring disposed longitudinally of said frame member, a reciprocable plunger passing lengthwise through said spring, a vertically disposed pivot near one end of said frame member, projecting through the top and bottom members thereof, a ball race member about said pivot immediately below the top frame member having a collar extending upwardly through said top frame member and surrounding the upper end of the pivot and serving as a bushing between the pivot and top frame member, a roller frame member on said pivot below said ball race disposed

in such manner as to cause the rollers thereof to engage that end of the plunger, and 20 guides for the plunger near the pivot end of the frame fastened to the frame on each side thereof and engaging the side edges and marginal portion of said plunger.

6. A spring hinge, including in combination, a helical spring, a tongue extending through said spring and beyond each end thereof, the tongue having shoulders providing abutments for the rear end of the spring, and side guides cooperating with 25 the tongue for controlling lateral and vertical movement thereof, said guides being disposed near the shouldered portion of the plunger when the same is in normal position.

DONALD E. WILLARD.

Certificate of Correction.

It is hereby certified that in Letters Patent No. 1,603,823, granted October 19, 1926, upon the application of Donald E. Willard, of Danville, Illinois, for an improvement in "Spring Hinges," errors appear in the printed specification requiring correction as follows: Page 2, line 5, strike out the word "roller"; page 3, line 130, claim 4, for the word "portion" read *portions*; and that the said Letters Patent should be read with these corrections therein that the same may conform to the record of the case in the Patent Office.

Signed and sealed this 7th day of December, A. D. 1926.

[SEAL.]

M. J. MOORE,
Acting Commissioner of Patents.
